MULTIPLE COMBUSTION CHAMBER JET TURBINE

Paul R. Haueter, Navarre, Ohio

Application February 20, 1951, Serial No. 211,829

3 Claims. (Cl. 60—39.39)

1

This invention relates to jet engines, and more particularly to jet engines of the turbine type employing multiple combustion chambers.

A main object of the invention is to provide a novel and improved multiple-combustion chamber jet turbine which is simple in construction, which is reliable in operation, and which is provided with sufficient control means for regulating the admission and compression of the combustion elements employed to propel the engine.

A further object of the invention is to provide an improved multiple-combustion chamber jet turbine which involves relatively inexpensive components, which is rugged in construction, which is light in weight, which is relatively compact in size, and which is particularly suitable for use as the power plant for aircraft.

Further objects and advantages of the invention will become apparent from the following description and claims, and from the accompanying drawings, wherein:

Figure 1 is a longitudinal, vertical, cross-sectional view taken through an improved multiple-combustion chamber jet turbine constructed in accordance with the present invention;

Figure 2 is an enlarged cross-sectional view taken on the line 2—2 of Figure 1;

Figure 3 is an enlarged cross-sectional view taken on the line 3—3 of Figure 1;

Figure 4 is an enlarged fragmentary, cross-sectional, detail view taken on the line 4—4 of Figure 2;

Figure 5 is an enlarged, cross-sectional, detail view taken on the line 5—5 of Figure 3;

Figure 6 is a cross-sectional view taken on line 6—6 of Figure 1.

Referring to the drawings, the jet turbine comprises an elongated, tubular body 11 which is provided at its forward end with the air intake opening 12, said opening being provided with the forwardly flared wall 13. The rear portion of the tubular body 11 is formed with the enlarged turbine chamber 14 having the rear exhaust opening 15. Secured axially in the forward portion of the body 11, as by the hollow radial arms 16, is a housing 17 provided with a forward bearing portion 18. Designated at 19 is a rear bearing portion secured axially in the turbine housing 14, as by the radial arms 20. Designated at 21 is a shaft journaled axially in the body 11 and the turbine housing portion 14 in the respective bearing elements 18 and 19. Mounted in the housing 17 is a generator 22 whose armature is secured to the shaft 21.

Mounted on the shaft 21 in the forward por-

2

tion of the housing 11 are a plurality of air compression vanes 23 arranged to build up air pressure in the intermediate portion of the body 11 responsive to rotation of shaft 21. Mounted on the rear portion of the shaft 21 are a plurality of turbine blades 24 which are arranged to develop torque on the shaft 21 responsive to jet action thereon of the gaseous products of combustion in the combustion chambers of the engine, as will be presently described.

Designated at 25 are a plurality of longitudinally extending, tubular conduits secured in the intermediate portion of the body 11 and arranged at equal angular spacings around the shaft 21. The forward ends of the conduits 25 are provided with inwardly directed elbows 26 whose inner ends open toward the axis of the body 11 and are located in a cylindrical surface coaxial with the body 11 with the centers of said inner ends in a common transverse, radial plane. The rear ends of the conduits 25 terminate also in a common transverse, radial plane at the forward end of the turbine housing portion 14, as shown in Figure 1.

Rotatably mounted on the intermediate portion of shaft 21 is a sleeve member 27 which is located inwardly adjacent the respective conduits 25. Secured to the sleeve 27 is a worm gear 28 which is meshed with a worm 29 carried on a shaft 30 journaled transversely in the housing and driven by an electric motor 31 mounted on the exterior of said housing, as shown in Figure 6. Motor 31 is energized by any suitable source of electric current, such as a vehicle storage battery.

Secured on the forward end portion of the sleeve 27 is a first valve rotor assembly 32 comprising a generally cylindrical body which is cut away at diametrically opposite portions, as shown at 33, 33 in Figure 2. In the specific embodiment of the invention illustrated in the drawings, there are eight evenly spaced conduits 25 and the cut-away portions 33 expose the ends of opposite pairs of elbow elements 26, 26, as shown in Figure 2, whereby air may be admitted into opposite pairs of conduits 25, while the remaining opposite pairs of conduits are closed off at their elbow elements 26. Secured to the rear end portion of the sleeve 27 is a valve disc 34 arranged to sealingly overlap the open ends of the conduits 25, said valve disc being formed with the diametrically opposite cut-away portions 36, 36 arranged to expose rear ends of diametrically opposite pairs of conduits 25, 25, while closing off the rear ends of the remaining pairs of diametrically opposite conduits 25, as shown in Figure 3. It will be seen, however, that the cut-away portions 36 of the disc member 34

lead the cut-away portions 33 of the valve rotor 32 by an angle equal to the angular spacing between centers of the adjacent conduits 25, assuming counterclockwise rotation of the sleeve 27, as viewed in Figures 2 and 3. For example, it will be seen that the leading edge 37 of the exhaust valve disc 34 leads the leading edge 38 of the air admission rotor valve 32 by an angle equal to the angular spacing between centers of successive conduits 25. This allows the air admitted into a conduit 25 to be compressed during the time required for the sleeve 27 to be rotated through the angle between successive conduits 25.

Connected to each conduit 25 through the wall of the body 11 are a pair of longitudinally spaced fuel injection nozzles 39 and 40, said nozzles being connected to a fuel supply conduit shown at 41. The supply conduit 41 leads to a suitable source of liquid fuel which may include a pump for developing the required pressure to inject the fuel intermittently into the conduit 25 through the nozzles 39 and 40 in the form of a spray in timed relation with the movement of the valve disc. Each conduit 25 is provided at its intermediate portion with an ignition plug 42 whose high voltage electrode is provided with a high voltage from a conventional distributor which is suitably timed to coincide with the injection of fuel in accordance with the rate of rotation of the sleeve 27, as by the provision of the breaker points 43, 44 operated by sleeve 27, a pair of said breaker points being provided for each of the ignition plug 42. The details of the ignition system are well known per se and form no part of the present invention, and will be obvious to those skilled in the art.

In operation, air is first admitted into a conduit 25 and at the same time exhaust gases escape from the rear end of said conduit, since there is an overlap between the cut-away portions 33 of rotor valve 22 and the cut-away portions 36 of exhaust valve disc 34 equal to the angular spacing between centers of successive conduits 25. Therefore, during the first stage of air admission into a conduit 25, exhaust gases escape from the rear end of the conduit. At the end of the time required for the leading edge 37 of valve disc 34 to move through an angle equal to the spacing between centers of adjacent conduits 25, the rear end of the aforementioned conduit 25 is closed, while the forward end of said conduit remains open allowing air to be forced into the conduit by the air compressive vanes 23 and allowing the pressure of the air to be built up in the conduit during the time required for the rotor 32 to close the forward end of the conduit. When the forward end of the conduit is closed, ignition occurs and combustion takes place with both ends of the conduit closed during the time required for the sleeve 27 to rotate through an angle equal to the angular spacing between centers of adjacent conduits.

At the end of this time the rear end of the conduit is uncovered by disc 34, while the forward end of said conduit remains still covered by rotor 32. The gaseous products of combustion exhaust from the rear end of the conduit and act on the turbine blades 24, transmitting torque to said blades. This jet action occurs through a time period required for the sleeve 27 to rotate through the angle between centers of successive conduits 25, and at the end of said time period the forward end of the conduit becomes uncovered and the above-described action is repeated. It will be apparent that the above cycle of operations takes place continuously at diametrically

opposite sides of the body 11, whereby torque is applied to the blades 24 at diametrically opposite points with respect to shaft 21. Similarly, the air compression action of the air compressor blades 23 takes place at diametrically opposite sides of the body 11 at the same time.

The vehicle batteries are charged by the generator 22 in a conventional manner, said batteries furnishing the power energizing the motor 31 which drives the sleeve 27. Since the speed of rotation of shaft 21 is governed by the force of the explosions in the respective conduits 25, the speed of shaft 21 may be regulated over a wide range by merely regulating the rate of injection of the fuel into said conduits, the speed of the sleeve 27 being independent of the speed of shaft 21.

The cylindrical arrangement of the air admission valve surfaces provided on the rotary valve 32 provides a substantial increase in efficiency as over comparable air admission valve arrangements, since the valve surfaces of the rotor 32 provide solid thrust heads resisting the explosion of the fuel mixtures in the conduits 25, thereby minimizing the possibility of leakage and providing higher compression in the combustion chambers. Furthermore, the cylindrical surfaces of the rotary valve 32 are of substantial longitudinal extent, whereby coverage of the inwardly directed openings of the elbows 26 will be provided regardless of relative longitudinal movement of the sealing surfaces of the valve rotor 32 with respect to the elbow openings such as may occur by thermal expansion of the body 11 and conduits 25 in a longitudinal direction relative to the valve rotor 32. It will be further noted that the efficiency of the engine will increase with speed due to the increased intake of air with forward motion of the engine.

While a specific embodiment of an improved jet turbine of the multiple-combustion chamber type has been disclosed in the foregoing description, it will be understood that various modifications within the spirit of the invention may occur to those skilled in the art. Therefore, it is intended that no limitations be placed on the invention except as defined by the scope of the appended claims.

What is claimed is:

1. A jet turbine comprising an elongated tubular body, a shaft journalled axially in said body, a plurality of air compression vanes mounted on said shaft in the forward portion of said body, a plurality of turbine blades mounted on said shaft in the rear portion of said body, a plurality of longitudinal, open ended tubular conduits secured in the intermediate portion of said body and being radially equally spaced in said body, each said conduit being coaxial of said shaft, a sleeve member rotatably mounted on a portion of said shaft intermediate said compression vanes and said turbine blades, a first valve rotor mounted on said sleeve member adjacent the forward end of said conduits, said valve rotor having an apertured portion successively aligned with the forward ends of said conduits as said shaft rotates, whereby to periodically open and close the forward ends of said conduits responsive to rotation of said sleeve member, a second valve rotor mounted on said sleeve member and adjacent the rear ends of said conduits and having an apertured portion successively aligned with said rear ends, whereby to periodically open and close the rear ends of said conduits, the leading edge of said second valve rotor being

spaced ahead of the leading edge of the first valve rotor by an angle equal to the angular spacings between the centers of the conduits, and the angular width of said apertured portions of said valve rotors being equal, fuel supply nozzles connected to the respective conduits, and fuel ignition elements mounted in said respective conduits and operable in timed relation to said valves.

2. A jet turbine comprising an elongated tubular body, a shaft journalled axially in said body, a plurality of air compression vanes mounted on said shaft in the forward portion of said body, a plurality of turbine blades mounted on said shaft in the rear portion of said body, a plurality of longitudinal open ended tubular conduits secured in the intermediate portion of said body and radially equally spaced in said body, each said conduit being coaxial of said shaft, a sleeve member rotatably mounted on a portion of said shaft intermediate said compression vanes and said turbine vanes, a first valve rotor mounted on said sleeve member adjacent the forward ends of the conduits and having diametrically opposed blanking elements, said blanking elements being movable into and out of engagement with the forward ends of said conduits to periodically close and open the forward ends of diametrically opposed groups of said conduits responsive to rotation of said sleeve member, a second valve rotor mounted on said sleeve member adjacent the rear ends of said conduits and having diametrically opposed blanking elements, said last named blanking elements being periodically movable into and out of engagement with the rear ends of said conduits to close and open the rear ends of diametrically opposed groups of said conduits, the leading edges of the blanking elements of said second valve rotor being spaced ahead of the leading edges of the blanking elements of the first valve rotor by an angle equal to the angular spacings between the centers of the conduits, and the angular width of each of the blanking elements of said first valve rotor being equal to the angular width of the blanking elements of said second valve rotor, fuel supply nozzles connected to the respective conduits, and fuel ignition elements mounted in said respective conduits and operable in timed relation with said valves.

3. A jet turbine comprising an elongated tubular body, a shaft journalled axially in said body,

a plurality of air compression vanes mounted on said shaft in the forward portion of said body, a plurality of turbine blades mounted on said shaft in the rear portion of said body, a plurality of longitudinal open ended tubular conduits secured in the intermediate portion of said body and radially equally spaced in said body, each said conduit being coaxial of said shaft, the open forward ends of said conduits being directed radially inwardly, a sleeve member rotatably mounted on a portion of said shaft intermediate said compression vanes and said turbine vanes, a first valve rotor mounted on said sleeve member adjacent the forward ends of the conduits and having diametrically opposed cylindrical blanking elements axially coextensive with the forward ends of said conduits, said blanking elements extending circumferentially by an amount at least sufficient to periodically open and close diametrically opposed pairs of the forward ends of said conduits responsive to rotation of said sleeve member, a valve disc mounted on said sleeve member adjacent the rear end of said conduits and having diametrically opposed pairs of apertures successively aligned with said rear ends of said conduits, whereby to periodically open the rear ends of diametrically opposed pairs of said conduits responsive to said rotation, the respective blanking elements being angularly spaced behind the respective pairs of apertures by an angle equal to the angular spacings between the centers of the conduits and the angular width of said blanking element being equal to the angular width of said apertures, fuel supply nozzles connected to the respective conduits, fuel ignition elements mounted in said respective conduits and operable in timed relation to said fuel supply nozzles, and a motor mounted on said body and drivingly coupled to said sleeve member.
